UNITED STATES PATENT OFFICE.

ELMER P. NICHOLS, OF MANCHESTER, NEW HAMPSHIRE, ASSIGNOR TO LACENE MANUFACTURING COMPANY, OF MANCHESTER, NEW HAMPSHIRE, A CORPORATION OF MAINE.

SKIVING-MACHINE.

1,205,104.

Specification of Letters Patent. Patented Nov. 14, 1916.

Application filed May 4, 1915. Serial No. 25,829.

To all whom it may concern:

Be it known that I, ELMER P. NICHOLS, a citizen of the United States, and resident of Manchester, in the State of New Hampshire, have invented an Improvement in Skiving-Machines, of which the following description, in connection with the accompanying drawings, is a specification, like letters on the drawings representing like parts.

My invention relates to machines for shaving, splitting or skiving leather, the object of my present invention being to render practicable and advantageous the skiving of the leather by means of a knife having a single bevel without the danger of gouging or improperly skiving the leather piece, my present application being a continuation of my application Ser. No. 875,377, filed December 3, 1914, where I have shown and described one embodiment or specific application of my invention which is generically set forth and claimed in the present application in connection with another species.

Said two species are, however, respectively claimed specifically in their respective applications.

It has long been considered desirable in leather splitting or skiving machines to employ a knife beveled on one side only, but this has been impossible because such a knife in the cutting machines heretofore provided has been so mounted as always to tend to gouge the leather, *i. e.* to dig into or cut into the leather beyond the extent desired. I have discovered that this tendency has been due to the relation of the work feeding mechanism and the knife, or rather, it has been due to the position of the knife with relation to the direction of feed of the stock at the cutting point or edge where the stock meets the knife.

My invention therefore, resides in the practical application of my discovery to such a provision of a single-bevel knife with relation to the work feeding mechanism as to eliminate this gouging or digging-in tendency.

Stated in general terms, my invention resides in the combination with a single-bevel knife of work feeding mechanism so related and relatively positioned that the body of the stock as it is fed against the edge of said knife is maintained substantially flat

and the knife is set at an angle or in an oblique plane so as to wedge off the skiving with just the wedging action required for even cutting. For ordinary purposes, as in skiving rather heavy, stiff leather, I provide means to keep the body of the stock in engagement with one side, preferably the bevel-side of the knife, while the other side, preferably the back-side or flat side of the knife (preferably close to the yielding feed roll or equivalent feeding device), is at such an angle to the direction of body-movement of the stock at the cutting point of the knife as to have a wedging action on the stock where it is being cut.

Stated less broadly, my invention, in its more restricted embodiment, requires that the single-bevel knife shall be so set with relation to the direction of feed of the stock at the cutting point or edge of the knife that each face of the knife has a wedging action on the stock. The knife in the latter case is preferably so positioned that the skiving comes off at the back-side of the knife while the body of the stock passes on the bevel-side of the knife.

In the accompanying drawings which I herewith present for more conveniently exhibiting my invention and explaining the principles thereof and the best mode in which I contemplate applying those principles, Figure 1 is a central, vertical, longitudinal section of a skiving machine containing a single-bevel knife so arranged and mounted with relation to the work feeding mechanism as to embody my invention. Fig. 2 is a vertical, transverse, sectional view looking from the end of the machine toward the cutting edge of the knife, and Figs. 3 and 4 are views of the machine in side elevation and top plan partly broken away and sectioned.

It will be understood that in the drawing I have endeavored merely to show a conventional skiving machine, so far as concerns the general details, merely as a convenient means of exhibiting and explaining my invention, the latter, however, not being restricted in any sense to this kind of a skiving machine, but having broad application to leather skiving, shaving and splitting machines in general. In a suitable frame 1 are mounted usual feed rolls 2, 3, the latter being shown as corrugated and yieldingly up-

held by springs 4, and the former vertically adjustable by adjusting blocks 5 and hand screw 6, both rolls being positively driven by sprocket chains 7, 8, engaging respectively sprocket wheels 9, 10 of the respective rolls, and sprocket wheels 11, 12 of shafts 13, 14 respectively, which are geared together by spur gears 15, 16 and provided with loose and fast pulleys 17, 18 on the shaft 14. In general, all the mechanism thus far described may have infinite variety within the spirit and scope of my invention, it being essential merely that there shall be some kind of stock feeding mechanism to cause the stock to be approached or directed to the cutting edge of the knife at the right angle or direction or in the right relation as required by my invention.

As herein shown, immediately behind the feed roll 3 is a heavy transverse ledge or knife supporting block 19, on which is adjustably secured by any suitable means, as by clamping bolts or screws 20, the single-bevel cutting knife 21, whose use it is the object of my invention to make possible.

Referring more particularly to Fig. 1, where my invention may most readily be apprehended, it will be seen that I have so mounted the knife 21 that its beveled side 22 is uppermost, facing the smooth roll or gage roll 2, while the flat side or back 23 of the knife extends obliquely rearward and downward adjacent the yielding feed roll 3. In this position the body of the stock passes between the bevel 22 and the gage roll 2 while the skinning is diverted downward by the back 23 of the knife and the corrugated roll 3. I prefer to have the bevel edge or side 22 of the knife arranged thus to receive the wear due to the friction of the leather pieces being fed along because this facilitates the proper sharpening of the knife, promotes economy and tends to maintain a straight edge. All the sharpening of a single-bevel knife is done on the bevel side and if the knife were reversed from the position shown in the drawings so as to have the cutting on the flat side or back side instead of on the bevel side, the friction of the leather, as the successive pieces of stock were fed along, would ultimately wear the back side hollow, so that a straight edge could no longer be secured by sharpening the bevel side. In other words, by so mounting the knife that the cutting is done on the bevel side and the body of the stock is therefore in engagement with the side where all the sharpening is done, thereby leaving the flat back side always flat or plane, the result is that a true, straight cutting edge is always readily maintained and the sharpening of the knife rendered easy and simple by being confined to the bevel edge while the opposite back side of the knife is left untouched by the sharpening tool and unworn.

away the skiving as fast as it is formed. For the reasons already explained, I prefer that this side of the knife shall be the back side. For securing the most complete results and best embodiment of my invention, the proper and best angle of the knife, therefore, with relation to the direction of feed of the stock at the cutting point is determined by the direction of feed, *i. e.*, the location of the knife with reference to the bight of the rolls (or direction of feed impulse, whatever may be the feeding mechanism), the bevel of the face 22 of the knife, and the tangency of the edge of the knife with relation to the adjacent member or portion of the feeding mechanism. In explanation of the latter feature, and still viewing Fig. 1, I mean that the angle of the knife must be such that the side of the knife which is adjacent the roll 3 tends, at each succeeding point rearward from the edge of the knife to leave the roll, or in other words, there is no point in said side which is closer to the roll than is the cutting edge. This permits the skiving to be wedged away by the knife under the coöperating pull of the roll with entire freedom and without any tendency to bind or choke between the knife and the roll. For instance, if, in Fig. 1, the rear end of the knife were dropped so as to tip the knife at such an angle that the back of the knife were closer to the roll 3 than the edge of the knife, there would result a crowding or squeezing of the skiving between the back of the knife and the roll 3. This would be improper. Referring now to the angle of the face 22 with relation to the direction of feed of the stock, it will be seen that there must always be, as just explained, with reference to the back of the knife, a divergence of the side 22 from the roll 2 at every point in said side back from the cutting edge, as distinguished from a convergence. The knife, therefore, must be mounted within the range of these two extremes, *i. e.*, so as to avoid on the one hand a convergence of the upper side (as herein shown, the side 22) with relation to the roll 2, and on the other hand, a convergence of the lower side (as herein shown, the side 23) with relation to the roll 3. Thus it will be seen that the opposite sides 22 and 23 adjacent the cutting edge of the single-bevel knife are mutually divergent from the respective adjacent rolls 2, 3. It has always heretofore been considered necessary to have skiving knives very thick and heavy to withstand great pressure so as not to spring at the edge toward the yielding feed roll. By my invention the knife may be much thinner as the knife is set at such an angle that it diverts the strains which have heretofore tended to spring the edge so that they tend to counteract each other.

65 To sum up some of the principal advan-

tages of my invention, the most important is the elimination of the liability or tendency to gouge and ruin the stock. The next in importance is the economy of time, labor and material, resulting from the use of a single-bevel knife. The third is the simplification of the work of keeping such a machine in order, as it requires much less skill, according to my invention, than with the old double-bevel knives. Not only is the original knife itself much less expensive, but it is a comparatively simple matter to maintain a proper straight edge because all the sharpening comes on the single bevel, the maintenance of an unvarying bevel is no longer so important as in the old double-bevel knives, the cutting edge may properly and readily be maintained thinner than heretofore and hence the knife adjusted closer in between the rolls, and the knife may be more easily and conveniently adjusted for stocks of different degrees of hardness and softness, etc.

I regard myself as the first to have succeeded in making it possible to use a single-bevel knife in a leather skiving machine, and also the first to employ such a knife so mounted that its back side operates to wedge away the skiving from the body of the leather piece being skived, and hence I wish it understood that in these respects considered both separately and together the invention is a pioneer and this is therefore entitled to be a foundation patent as to these broad features. The generic claims to my invention are contained herein, and my aforesaid copending application, so far as it relates to this invention, is subordinate hereto. As implied in the foregoing statements of this paragraph, and as already stated in the earlier part of this specification, my invention is capable of a wide range of physical embodiments, and therefore, excepting as otherwise restricted, in certain of the claims, I am not limited to the particular mechanical construction, arrangement and relation of parts shown in the drawings. I have used the word "skiving" to include the cutting off of one side or portion of a leather piece in or parallel to the general plane of the piece, and therefore to include evening, shaving, splitting, as distinguished from the transverse cutting or beveling of a leather piece, in making belts for instance, where the opposite ends are beveled or cut through diagonally, in order to make a proper splice. The latter operation is not skiving in the proper sense as none of the problems and difficulties which are solved by my invention are there presented, and hence almost any kind of a knife can be used. In explaining and defining my invention, I have referred to the direction of feed of the stock at the cutting point and have referred to the feeding mechanism,

meaning thereby to characterize broadly these features and relations without limitation to any particular mechanism or relation. In the machine of the drawings, the 5 feeding mechanism is of the common type of feed roll machines in which the stock is nipped between the rolls and pushed by said nipping engagement toward and onto the knife. This, however, is only illustrative, 10 being one of many kinds of feeding mechanism. If the feeding mechanism were of such a kind that it should vary the direction of approach of the stock to the edge of the knife at said edge, the critical direction 15 to be considered in connection with my invention would be the direction which the stock in fact might have at the cutting point or edge of the knife and not the direction of movement which the stock might have at 20 any other point either beyond or back of said cutting edge.

My invention is accordingly further described and defined in the form of claims, as follows:

25. 1. In a machine of the kind described, the combination with stock feeding mechanism constructed and arranged to maintain the stock substantially flat and plane, of a single-bevel knife having its bevel-side 30 mounted to engage with the body of the stock being skived, and so set with relation to the direction of feed of the stock at the cutting edge of the knife that the back side of the knife has a wedging action on the 35 stock, said feeding mechanism including unyielding means for holding the side of the stock adjacent thereto at a fixed distance from said bevel-side of the knife.

2. In a machine of the kind described, the 40 combination with stock feeding means constructed and arranged to maintain the stock substantially flat and plane, of a single-bevel knife so set with relation to the direction of the feed of the stock at the cutting point that each face of the knife has a wedging action on the stock, said feeding mechanism including means located on that side of the knife which receives the body of the stock, constructed and arranged to co-

operate with said knife, so set, to maintain 50 the side of the stock adjacent said means at a fixed distance from the cutting edge of the knife.

3. In a machine of the kind described, stock feeding mechanism, including a yielding feed roll, and a single-bevel knife, having its cutting edge close to the bight of said roll and its adjacent side extending thence rearwardly and divergently from said roll and yet obliquely to the direction 60 of feed of the stock at the cutting edge of said knife, said feeding mechanism including means opposite said yielding roll and knife edge constructed and arranged to co-operate with said knife, so set, and with 65 said roll to maintain the side of the body of the stock adjacent said means at a fixed distance from the cutting edge of the knife.

4. In a machine of the kind described, feed rolls for receiving between them successive pieces of stock and positively feeding said stock to be skived, and a single-bevel skiving knife mounted rigidly behind said rolls with its cutting edge extending between the rolls close to the bight thereof 70 and having its opposite sides adjacent said edge mutually divergent from the respective adjacent rolls at all points back of the cutting edge, one of said rolls being yielding and close to the adjacent side of the 75 knife and the other roll being unyielding and at a greater distance from the adjacent side of the knife to permit the passage of the body of the stock, said latter roll being so positioned with relation to the other roll 80 and to the knife, mounted as stated, as to maintain the side of the body of the stock contacting therewith at a fixed distance 85 from the cutting edge of the knife throughout the skiving or splitting operation. 90

In testimony whereof, I have signed my name to this specification, in the presence of two subscribing witnesses.

ELMER P. NICHOLS.
